UNITED STATES PATENT OFFICE.

JOHN T. CULLEN, JR., OF CLINTON, IOWA.

AUTOMATIC STOKER FOR FURNACES.

Application filed September 26, 1921. Serial No. 503,307.

To all whom it may concern:

Be it known that I, JOHN T. CULLEN, Jr., a citizen of the United States, residing at Clinton, in the county of Clinton and State 5 of Iowa, have invented new and useful Improvements in Automatic Stokers for Furnaces, of which the following is a specification.

This invention relates to automatic stokers for furnaces and has for one of its objects the provision of a stoker the operation of which is responsive to temperature or pressure conditions within the furnace.

Another object of the invention is the provision of a stoker in which the mechanical elements are actuated through the agency of fluid pressure which is controlled by a physical condition in the furnace dependent upon the state of the fire.

Another object of the invention is to provide an automatic stoker in which two sets of rocking grate bars, one set of which is arranged in alternate relation to the other are successively operated by the movement 20 in one direction of a fluid pressure actuated plunger, the admission of fluid to said plunger being controlled by variation in the temperature of the furnace fire.

A further object of the invention is to provide in an automatic stoker of the class described a spring for returning the grate bars immediately after they have been rocked by the fluid pressure actuated means, said grate bars being, in addition, presently 30 turnable by the fluid pressure means in the event of breakage of the spring means, so as to avoid damage to the grate bars by leaving them projected into the fire.

A still further object of the invention is 40 to provide a stoker in which the elements operating the grate bars are moved by a fluid pressure actuated plunger, the admission of fluid to which is controlled by a valve, automatically responsive to a physical condition within the furnace resulting 45 from the state of the fire.

And, in the embodiment specifically disclosed in the drawings in which the furnace is provided with a boiler and the fluid pressure for operating the plunger is derived 50 from water in a pressure main, an object of the invention is to connect the bleed passage which is provided for the pressure side of the distributing valve to the boiler and to 55 associate therewith means for controlling the flow through said bleed passage as to

feed to the boiler water at a rate sufficient to maintain a constant level therein.

For the attainment of these ends and the accomplishment of other new and useful 60 objects, as will appear, the invention consists in the features of novelty in the construction, combination and arrangement of the several parts generally shown in the accompanying drawings and described in the 65 specification, but more particularly pointed out in the appended claims.

In the drawings:—

Figure 1 is a side elevation of a furnace equipped with my automatic stoker. 70

Figure 2 is a front elevation of the same furnace.

Figure 3 is a plan view of the grate.

Figure 4 is a slide elevation of the grate shown in Figure 3. 75

Figure 5 is a longitudinal view in detail of one of the grate bars.

Figure 6 is a detail view showing the distributing valve and the bleed passages leading to the boiler. 80

In the drawings, the furnace is represented by the numeral 1 and is provided with the front wall 2 which forms the support for one end of a boiler 3. In the lower part of the furnace beneath the boiler is the 85 grate 4 which inclines rearwardly from the fire door 5 of the furnace to the ash plate 6 which is preferably formed of masonry and is adjacent the ash pit 7. Fuel is fed at the fire door 5 and an ash door 60 is located at the bottom of the front wall of the furnace 90 below the grate. On the exterior of the front wall 2 of the furnace is arranged the major portion of the mechanism by which the grate bars are automatically operated. 95

Referring more in detail to the parts the grate comprises the inclined side members 8 spaced apart the width of the grate bars and each provided in its upper surface with semi-cylindrical bearing recesses 9 for the 100 reception of the similarly shaped lugs 10 on the opposite ends of the grate bars. Each of the grate bars consists of a casting having a flat upper surface 11 constructed with spaced bars and a cylindrical longitudinal apron 12, concave on its rear surface extending through an arc of substantially 90°. Said casting is provided at its opposite ends with projecting semi-cylindrical bearing 105 trunnions the upper surface of each of 110 which is in the plane of the upper surface of the grate bar, said trunnions projecting

rearwardly of said grate bars so that the axial line through said trunnions is in alignment with the rear edge of the grate bar. Secured to the lower edge of the apron 12 and preferably formed integral therewith is the lever 13 provided near its lower end with a slot 16 for connection with the draw bar 14 presently to be described. There are two draw bars, 14 and 14' respectively one 10 on each side of the grate and the grate bars are connected therewith alternately in gangs so that every alternate grate bar is connected to the draw bar on one side and the remaining grate bars to the draw bar on the 15 other side. The connection of each grate bar with its respective draw bar is by means of a pin 15 secured to said draw bar and projecting through the slot 16.

In the operation of the device the bars 14 20 are successively drawn toward the front of the furnace. This causes one set of alternately arranged grate bars to rise to the dotted line position shown in Figure 1 dumping the coals which they support upon 25 the alternate bars, which at this time lie flat. The first set of bars then return to position and the other set rise dumping the fire which they carry upon the bars of the first set which now lie flat. In this way the 30 fire is advanced slowly toward the rear of the grate and by the time the last grate bar is reached combustion is practically at an end and the ashes are deposited upon the ash-plate 6 from which they are raked at 35 appropriate intervals into the ash-pit 7. The aprons 12 prevent the fire falling between the grate bars when they are tilted and also keep the coals and clinkers from lodging therebetween.

40 The mechanism for operating the draw bars 14 and 14' comprise bell-crank levers 17 and 17' one for each bar as clearly shown in Figure 2. The bell-crank levers are pivoted at 18 and 18', each to a bracket 19 secured to the front wall of the furnace. One arm of each bell-crank is connected to the outer end of the corresponding draw bar by a pin 20 sliding in the slot 21 in the arm of said bell-crank. Springs 22 and 22' return 45 the bell-cranks and the draw bars 14 and 14' respectively connected thereto, to normal position after they have been actuated and a spring 23 between the front wall of the furnace and the end of each draw bar 14 50 prevents undue shock or jar in returning the grate bars to normal position.

Secured to the front of the furnace wall at distance above the brackets 19 are the 60 pairs of brackets 24 and 25. In each pair of brackets is journalled a rock shaft, one of which, designated by the numeral 26 is provided near its end with an arm 27 carrying at its end a pivoted shackle 28 to which is connected at one end a rod 29 the other 65 end of which makes connection by means of

a shackle 30 with the free arm of the bell-crank lever 17. A turn-buckle 31 intermediate the ends of the rod 29 permits the length of the latter to be adjusted.

The rock shaft 32 which is journalled in 70 the pair of brackets 25 is similarly provided at its outer end with an arm 33 which is connected to the free arm of the bell-crank 17' by means of a sequence of mechanism similar to that described in connection with the 75 rock shaft 26. Between the brackets of each pair the rock shafts 26 and 32 are respectively provided with the rigidly attached dogs 34 and 35. These dogs are of equal length and the outer end or nose of each projects into 80 the path of a U-trip 36 carried at the outer end of a vertically reciprocating plunger rod 37 which passes through a stuffing box 38 into a cylinder 39 where it is secured to the piston 40. One end of each rock shaft is 85 provided with a hand crank to permit manual operation of the stoker when desired.

The piston 40 is arranged to reciprocate in the cylinder and when on its upward stroke the U-trip 36 engages first the nose of the dog 34 raising said dog and partially rotating the rock shaft 26 which movement elevates the arm 27 and rotates the bell-crank 17 pulling out the draw bar 14 and operating 90 one set of grate bars. As the U-trip continues upward the nose of the dog 34 escapes therefrom and the parts, including the grate bars which have just been elevated, are returned to normal position by the spring 95 22. The U-trip, continuing its upward 100 movement engages the nose of the dog 35 raising the latter and operating the rock shaft 32 lifting the arm 33 which pulls up the bell crank 17' raising the other alternate set of grate bars which are returned to normal 105 position in a manner similar to that of the first set of grate bars, when the nose of the dog 35 has slipped from engagement with the U-trip 36.

The piston 40 is actuated by fluid pressure taken from any convenient source such as steam within the boiler, water from a town pressure main or oil from a closed pressure circulation system. In the embodiment here disclosed the pressure is derived 110 from water taken from the main 42. A two way distributing valve 43 is provided by means of which each side of the piston 40 is alternately put in communication with the water main and subjected to the pressure of 115 the fluid therein.

This valve is shown in detail in Figure 6 in which 44 is the casing of the valve connected, at 90° intervals with the supply conduit 42, the pipe 61 leading to the top of the cylinder 39, the pipe 45 leading to the bottom of said cylinder and an exhaust conduit 46 for draining either side of said cylinder when it is relieved from pressure. A barrel valve 47 operates in this casing and is cut away on 120 125 130

opposite sides forming passages 48 and 49 which by turning said valve may place the top or bottom of the cylinder in communication with the water main and at the same time place the other end of the cylinder in communication with the exhaust conduit. As pressure is usually maintained for a considerable interval of time in either end of the cylinder during the operation of the device, bleed passages 56 are provided in the valve 43 to prevent leakage of fluid past the piston 40.

The operating handle 50 of the valve 43 is connected through a link 51, and lever 52 with a pressure diaphragm 54 in communication with the boiler. A sliding weight 55 arranged on one end of the lever 52 determines at what pressure the diaphragm will operate. The valve and its actuating parts are so arranged that when the fire under the boiler is low and the pressure within the boiler is light said pressure, through the diaphragm, will turn the valve so as to put the lower end of the piston 40 in communication with the source of fluid pressure 42. The piston will then raise the U-trip actuating the dogs 34 and 35 in a manner hereinbefore described, rocking the grate bars and so stimulating the fire. The valve 43 will maintain the lower side of the cylinder in communication with the water main 42 until the pressure of steam within the boiler has reached a predetermined degree at which time the diaphragm 54 will cause the valve 43 to turn putting the upper end of the cylinder in communication with the source of fluid pressure and the lower end in communication with the exhaust conduit 46. This will cause the descent of the U-trip which will freely pass the noses of the dogs 34 and 35 since the latter will yield against the pressure of the spring 22. The U-trip will then remain in its lowest position until cooling of the fire so lowers the pressure of the steam in the boiler as to cause the valve 43 to be again turned to admit fluid pressure to the lower end of the cylinder when the automatic stoking of the fire will be repeated.

Should for any reason either of the springs 22 or 22' become broken or disconnected the dogs 34 or 35 will remain extended in the path of the U-trip 36 which will on its descent, impelled by the pressure on the upper side of the piston 40 positively depress said dogs and through them, push the grate bars back into position thus avoiding any damage which would come to them through having been exposed for a long time in a false position to the fire.

In order to maintain the water level in the boiler 3 constant, it is desirable to connect the bleed passages 56 to the boiler which may be done by uniting them into a single conduit 57 communicating directly with the boiler. By arranging the bleed

passages 90° apart as shown, one is always in communication with a part of the valve which is under the pressure of the water in the main 42. By providing an appropriate pass valve 58 and a check valve 59 in the conduit 57 the flow of water through said bleed passage may be so adjusted as to compensate for the loss of water in the boiler through evaporation and other causes and maintain a constant level of water therein. 75

It is obvious that various changes may be made in the details of construction without departing from the invention and it is therefore to be understood that this invention is not to be limited to the specific construction 80 shown and described.

Having described my invention what I claim as new and desire to secure by Letters Patent, is:—

1. In combination with a source of heat supply, an automatic stoker comprising movable sets of grate bars, fluid pressure actuated means communicating with said source of heat supply for alternately moving said sets of bars, and means for returning said bars at once to normal position after said movement. 85

2. In combination with a furnace and a boiler associated therewith, an automatic stoker therefor comprising movable sets of grate bars, fluid pressure actuating means communicating with said boiler and movable in one direction for operating said grate and means for returning said bars immediately to normal position after operation, and 95 means responsive to the pressure in said boiler for controlling the connection of said fluid pressure system to said operating means. 100

3. In combination with a furnace, an automatic stoker therefor comprising a grate, sets of rocking bars for said grate, the bars of one set being arranged alternately to the bars of another set, operating means for each set of bars, each operating means being 105 constructed to simultaneously operate the bars of its set and a fluid pressure device having a plunger and means successively engaged by said plunger when moving in one direction to sequentially rock the sets of 110 grate bars. 115

4. An automatic stoker comprising sets of alternately arranged grate bars, means for operating said sets of bars comprising a rock shaft for each set operatively connected 120 thereto, a dog on each rock shaft, a cylinder, a plunger within said cylinder, trip means carried by said plunger, said dogs extending into the path of said trip means, said dogs being successively engageable by said trip means when the plunger is moved in one direction and yieldingly movable from the path of said trip means when the plunger moves in the other direction. 125

5. An automatically controlled stoker com- 130

- prising sets of alternately arranged grate bars, means for operating said sets of bars comprising a rock shaft for each set operatively connected thereto, a dog on each rock shaft, a fluid pressure actuated plunger, a spring for each dog normally holding said dog in grate closing position, a spring normally maintaining said dogs in the path of said plunger, said dogs being successively 10 operated by said plunger when moving in one direction to rotate said rock shafts and yieldably movable from the path of said plunger to permit passage of the latter when moving in the other direction.
- 15 6. An automatic stoker comprising sets of alternately arranged grate bars, a rock shaft for each set of grate bars for operating the same, a dog secured to each rock shaft, a fluid pressure cylinder, a plunger in said 20 cylinder, means reciprocable with said plunger for successively actuating said dogs to operate the sets of grate bars, means for returning said sets at once to normal position after said actuation, a source of fluid 25 pressure, and means for putting said source of fluid pressure into communication with either end of said cylinder.
7. An automatic stoker comprising sets of alternately arranged grate bars, a rock shaft 30 for each set of grate bars for operating the same, a dog secured to each rock shaft, a fluid pressure cylinder, a plunger in said cylinder, means reciprocable with said plunger for successively actuating said dogs 35 to operate the sets of grate bars, means for returning said sets at once to normal position after said actuation, a source of fluid 40 pressure, and a two way valve for putting said source of fluid pressure into communication with either end of said cylinder.
8. In a furnace, an automatic stoker therefor comprising sets of alternately arranged 45 grate bars, a rock shaft, for each set of grate bars, for operating the same, a dog secured to each rock shaft, a fluid pressure cylinder, a plunger in said cylinder, means movable with said plunger and successively engageable with said dogs for operating said rock shafts, a source of fluid pressure, means for 50 putting said source of fluid pressure into communication with either end of said cylinder, said means being responsive to a physical condition within said furnace dependent upon the state of the fire.
- 55 9. In a furnace, an automatic stoker therefor comprising sets of alternately arranged 60 grate bars, a rock shaft, for each set of grate bars, for operating the same, a dog secured to each rock shaft, a fluid pressure cylinder, a plunger in said cylinder, means movable with said plunger and successively engageable with said dogs for operating said rock shafts, a source of fluid pressure, a valve for putting said source of fluid pressure 65 into communication with either end of

said cylinder, said valve being responsive to a physical condition within said furnace dependent upon the state of the fire.

10. In combination a furnace, a boiler associated therewith, an automatic stoker 70 therefor comprising sets of alternately arranged grate bars, means for operating said sets of bars comprising a rock shaft for each set for operating the same, a dog rigidly secured to each rock shaft, a fluid pressure cylinder, a plunger in said cylinder, means carried by said plunger successively engageable with said dogs for operating said rock shafts, a source of fluid pressure, means for putting said source of fluid pressure into 75 communication with either end of said cylinder, and means responsive to pressure within said boiler for controlling said means.

11. In combination a furnace, a boiler associated therewith, an automatic stoker therefor comprising sets of alternately arranged grate bars, means for operating said sets of bars comprising a rock shaft for each set, a dog rigidly secured to each rock shaft, a fluid pressure cylinder, a plunger in said cylinder, means carried by said plunger successively engageable with said dogs for operating said rock shafts, a source of fluid pressure, a valve for putting said source of fluid pressure into communication with either end of 90 said cylinder, and means responsive to pressure within said boiler for controlling said valve.

12. An automatic stoker comprising sets 100 of alternately arranged grate bars, means for operating said sets of bars comprising a rock shaft for each set operatively connected thereto, a dog on each rock shaft, a fluid pressure cylinder, a plunger working in said cylinder, means moving with said plunger and successively engageable with said dogs for operating said rock shafts, a valve, a source of fluid pressure communicating therewith, conduits leading from said valve 105 communicating with the opposite ends of said cylinder, an exhaust conduit communicating with said valve and means for operating said valve to put either end of said cylinder into communication with the source of fluid pressure and the opposite end into communication with said exhaust conduit.

13. In combination a furnace, a boiler associated therewith, an automatic stoker therefor comprising sets of alternately arranged grate bars, means for operating said sets of bars comprising a rock shaft for each set operatively connected thereto, a dog on each rock shaft, a fluid pressure cylinder, a plunger working in said cylinder, means moving with said plunger and successively engageable with said dogs for operating said rock shafts, a valve, a source of fluid pressure communicating therewith, conduits leading from said valve 115 communicating with

the opposite ends of said cylinder, an exhaust conduit communicating with said valve and means responsive to the pressure in said boiler for operating said valve to put 5 either end of said cylinder into communication with the source of fluid pressure and the opposite end into communication with said exhaust conduit.

14. In combination a furnace, a boiler associated therewith, an automatic stoker therefor comprising sets of alternately arranged grate bars, means for operating said sets of bars comprising a rock shaft for each set operatively connected thereto, a dog on 15 each rock shaft, a fluid pressure cylinder, a plunger working in said cylinder, means moving with said plunger and successively engageable with said dogs for operating said rock shafts, a valve, a source of fluid pres-

sure communicating therewith, conduits 20 leading from said valve communicating with the opposite ends of said cylinder, an exhaust conduit communicating with said valve and means responsive to the pressure in said boiler for operating said valve to 25 put either end of said cylinder into communication with the source of fluid pressure and the opposite end into communication with said exhaust conduit and a bleed passage leading from said valve to said boiler. 30

In testimony whereof I have hereunto set my hand in presence of two subscribing witnesses.
